UNITED STATES PATENT OFFICE

HARRY A. HOKE, OF ALTOONA, PENNSYLVANIA

LEVER FOR SHAKING GRATES

Application filed May 23, 1928. Serial No. 279,980.

This invention relates to levers for shaking grates and more particularly to levers for shaking the grates of locomotive fire boxes.

In locomotives which are not equipped with power shaking apparatus for the grates, it is customary to provide, on a grate bar or on a link which connects a plurality of grate bars, a suitably projecting stud or stub shaft with which a removable lever is adapted to 10 cooperate for the purpose of shaking the grate bars. Heretofore, such levers have been formed either by upsetting the end of a wrought iron bar and piercing the same to provide a socket to slip over the stud or by 15 suitably welding a socket to the end of a bar of iron or steel.

Shaking levers are usually from four to five feet long and require considerable expenditure of effort on the part of the fireman, particularly where the fire boxes are 20 large or where clinkers accumulate between the grate bars. It has been found that both the upset and pierced type and the welded type, if carefully made, are satisfactory, but 25 often defects occur in the metal resulting from the upsetting or the welding which cause breakage of the lever while in use. In several instances such breakage has resulted in serious injuries to the fireman who was exerting great effort at the time of the breakage 30 and was either precipitated against the hot rear wall of the fire box and burned or thrown to the floor of the cab compartment and injured. Unfortunately, defects in the metal 35 occurring as a result of the upsetting or welding are not readily detected until the breakage occurs. The present invention seeks to overcome the above difficulties and to simplify the construction of the lever used for 40 shaking grates.

It is therefore an object of the present invention to provide a novel and improved form of lever for shaking grates.

More particularly, it is the object of the 45 invention to provide a grate shaking lever formed in two parts, including a bar having a handle at one end and an enlarged portion at the opposite end adapted to be received in 50 and permanently secured to a hollow seam-

less member having a socket extending beyond the end of the bar.

Other and further features and objects of the invention will be more apparent to those skilled in the art upon a consideration of the accompanying drawings and following specification, wherein is disclosed a single exemplary embodiment of the invention, it being understood, however, that various changes may be made therein such as fall within the 55 scope of the appended claim without departing from the spirit of the invention.

In said drawings:

Figure 1 is a side elevation of a lever for shaking grates constructed according to the 60 present invention;

Figure 2 is a partial side elevation on an enlarged scale showing the sleeve in vertical section;

Figure 3 is a transverse section taken on line 3—3 of Figure 2; and

Figure 4 is a vertical section taken on line 4—4 of Figure 2.

A lever constructed according to the present invention comprises two essential parts, 75 the bar 10 and the tube 11. The bar is preferably rolled or drop forged from open hearth steel and is more or less rectangular in cross section and tapers upwardly from the point 12 to the point 13 where it is enlarged and made substantially cylindrical to form the handle 14. Below the point 12 there is a blunt wedge-like enlargement 15 which preferably has parallel sides 16 as shown in Figure 3 and converging edges 17. The cross section anywhere within the enlargement 15 is that of an elongated rectangle.

The tube portion 11 is preferably formed from a section of seamless steel tubing properly shaped to have one end fit over the enlarged part 15 of the bar and the other end to provide the socket 18 adapted to fit over the stud on the grate bar. As shown in Figure 2, the tube preferably is flared in both directions from the restricted center 19, but 85 its widest walls remain parallel to each other as do the sides 16 of the enlarged portion of the bar. The upper end of the tube is so formed as to have an exact fit on the enlargement at the end of the bar which is then 90 100

driven into the tube, after which suitable holes are drilled through the two parts and fastening means, such as the rivets 20, applied so as to retain the two parts secured together. That portion of the tube extending below the end of the bar forms the socket 18 previously referred to.

By making the tube or socket of a piece of seamless steel tubing, the likelihood of any flaw existing therein is reduced to a minimum and danger of accidents almost entirely eliminated. At the same time the bar can be more easily and cheaply constructed and can be made lighter in weight than heretofore.

Having thus described the invention, what is claimed as new and desired to be secured by Letters Patent is:

In a lever for shaking locomotive grates, in combination, a metal shaker bar having an enlarged portion at one end, said portion being rectangular in cross section and having two parallel faces and two faces converging toward the end of the bar, a length of seamless steel tubing having walls of uniform thickness and substantially twice the length of said enlarged portion, a portion of said tubing closely fitting over said enlarged portion of said bar, means fastening said tubing and bar together and a portion of said tube extending beyond said bar and forming a socket to engage a shaker stud.

In testimony whereof I hereunto affix my signature.

HARRY A. HOKE.
